UNITED STATES PATENT OFFICE.

WILLIAM T. BUMSTEAD, OF BEATRICE, NEBRASKA, ASSIGNOR OF ONE-HALF
TO HENRY M. HILL, OF SAME PLACE.

ATTACHMENT FOR BABY-CARRIAGES.

SPECIFICATION forming part of Letters Patent No. 447,660, dated March 3, 1891.

Application filed November 11, 1890. Serial No. 371,077. (No model.)

To all whom it may concern:

Be it known that I, WILLIAM T. BUMSTEAD, a citizen of the United States, residing at Beatrice, in the county of Gage and State of Nebraska, have invented certain new and useful Improvements in Attachments for Baby-Carriages; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to certain new and useful improvements in attachments to baby-carriages; and it has for its objects among others to provide a simple, cheap, and durable attachment readily applied to carriages now 20 in use, and which shall serve to keep the child in position in the seat when desired, give it a place to rest its arms squarely in front, keep the playthings from getting out of its reach, and which may be used either side up.

25 I provide a thumb-screw which serves the double function of holding the table onto the standard or support and also as a means for attaching the toys so that they cannot be thrown out of the reach of the baby.

30 Other objects and advantages of the invention will hereinafter appear, and the novel features thereof will be specifically defined by the appended claims.

The novelty in the present instance resides 35 in the peculiarities of construction and the combinations, arrangement, and adaptation of parts, all as more fully hereinafter described, shown in the drawings, and then particularly pointed out in the claims.

40 The invention is clearly illustrated in the accompanying drawings, which, with the letters of reference marked thereon, form a part of this specification, and in which—

Figure 1 is a perspective view illustrating 45 my attachment in position. Fig. 2 is a perspective view showing the attachment hung up, as when not in use in a carriage, forming a bracket.

Like letters of reference indicate like parts 50 in both views.

Referring now to the details of the draw-

ings by letter, A designates a portion of a baby-carriage of known construction. All complete baby-carriages have a removable seat, some sloping and some perpendicular at the outer 55 or front edge. When in position, the bottom of the post-brace of my attachment stands parallel with and tight against the lower front edge of the seat, but does not necessarily depend on the seat for its support, as it will 60 neither tip forward nor backward without the seat in place, being securely held in position; but the seat prevents any possibility of the table turning around sidewise.

B is the table, which may be made of the 65 desired size and shape, preferably, however, that shown in the drawings. This table, or what may be called the "table-top," is provided upon its under side with two cleats, staples, or like devices a, secured thereto in 70 any suitable manner and adapted to receive the horizontal portion or arm of the standard. These cleats or staples are arranged, preferably, one near each edge of the table, so as to better hold the said arm. The table-top is provided with a surrounding strip b, which extends a distance beyond the faces of the top upon either side to form a guard to prevent articles placed thereon from being easily 75 knocked off. This strip is notched at a point 80 opposite one of the cleats or staples, as shown at c, to receive the arm of the standard, as shown.

D is the standard or support. It is formed with a long horizontal arm C, which is of such 85 size and length as to fit the cleats on the under side of the table-top and to extend nearly across the table-top, so as to give it a firm support. A pin or other suitable stop d is provided to limit the movement of this arm, 90 the stop being held in the cleat and so arranged that when the end of the arm strikes it it brings the hole in the end of the arm coincident with the hole in the table-top through which the thumb-screw passes. The standard 95 is also formed with a foot E, adapted to be secured to the bottom of the carriage. It extends at right angles to the length of the standard and is provided with a hole f, through which the securing means passes. It is also 100 provided with a foot-brace F, of the form shown, so as to give stability to the same.

5 G is a bolt-plate designed to be screwed onto the under side of the bottom of the carriage, the central portion being provided with a screw-threaded hole *g* to receive the fastening-bolt *G'*, which passes through the hole *f* in the foot and engages the said screw-threaded hole in the bolt-plate, as shown. This forms a very neat, firm, and readily-affixed means of fastening the device removably in 10 place.

15 The vertical portion of the standard is padded, as shown at *H*, so as to prevent injury to the legs of the child when the table is in position in the carriage.

20 I is a thumb-screw engaged in the threaded opening in the table-top and designed to pass through the same and engage the hole in the end of the arm of the standard when the latter is in position. The upper portion of this 25 thumb-screw serves as a means of securing the playthings so they cannot get out of the reach of the child. They may be affixed to the thumb-screw by strings or in any other manner.

25 The baby can be readily seated or taken up without removing the attachment, and when desired to lay the child down in the carriage it takes but a moment to remove the attachment. When not in use, the device

30 may be hung up upside down, the standard resting between two supports, as nails, a proper distance apart and catching at the point where the foot-brace joins the post. It then forms a bracket for the toys or other uses, as seen in Fig. 2. The toys fastened 35 upon the other side can be tossed up without unfastening them.

What I claim as new is—

1. The combination, with the standard having horizontal arm and foot and foot-brace, of 40 the table-top provided with cleats to receive the said horizontal arm and means for detachably securing the parts in place, as set forth.

2. The combination, with the standard 45 formed with horizontal arm and foot, of the table-top provided with cleats upon the under side and a stop in one of the cleats, the foot-brace, and the thumb-screw passed through from the upper side of the table-top 50 and engaging a hole in the end of the said arm, substantially as specified.

In testimony whereof I affix my signature in presence of two witnesses.

WILLIAM T. BUMSTEAD.
